HEADLIGHT BEZEL FOR AUTOMOBILES OR THE LIKE

Eugene Bordinat, Jr., 1455 Lakewood Road,
Bloomfield Hills, Mich.

Filed Sept. 21, 1961, Ser. No. 66,785

Term of patent 7 years

(Cl. D48—32)

FIG. 1 is a front elevational view of a headlight bezel for automobiles or the like showing my new design;

FIG. 2 is a side elevational view of the right side of the headlight bezel as viewed in FIG. 1;

FIG. 3 is a side elevational view of the left side of the headlight bezel as viewed in FIG. 1;

FIG. 4 is a sectional view taken on the line 4—4 of FIG. 1;

FIGS. 5 and 6 are enlarged partial sectional views taken on the lines 5—5 and 6—6, respectively, of FIG. 1;

FIG. 7 is a plan view of FIG. 1;

FIG. 8 is a sectional view taken on the line 8—8 of FIG. 1; and

FIGS. 9 and 10 are enlarged partial sectional views taken on the lines 9—9 and 10—10, respectively, of FIG. 1.

I claim:

The ornamental design for a headlight bezel for automobiles or the like, substantially as shown.
